(57) **CLAIM**

The ornamental design for an automotive air intake system, as shown and described.

DESCRIPTION

FIG. 1 is a top plain view of the automotive air intake system showing our new design;

FIG. 2 is a left side elevation view of the automotive air intake system showing our new design;

FIG. 3 is a front elevation view of the automotive air intake system showing our new design; and,

FIG. 4 is a top perspective view of the automotive air intake system showing our new design.

The broken line shown in the drawings are for the purpose of illustrating portions of the article that form no part of the claimed design.
